UNITED STATES PATENT OFFICE.

LEE R. BENN, OF TAMA, IOWA.

SPARK-PLUG.

1,307,176.

Specification of Letters Patent. Patented June 17, 1919.

Application filed July 11, 1918. Serial No. 244,419.

To all whom it may concern:

Be it known that I, LEE R. BENN, a citizen of the United States, residing at Tama, in the county of Tama and State of Iowa, 5 have invented certain new and useful Improvements in Spark-Plugs, of which the following is a specification.

This invention relates to new and useful improvements in spark plugs, and the primary object of the invention is to provide a spark plug which will prevent carbon deposits forming on the lower end of the main electrode and short circuiting the device which will prevent its proper operation. 15 This type of spark plug will tend to keep the adjacent points of the spark gap clean, so as to insure a positive spark during its operation.

The invention has for its primary object 20 to provide an improved electrode of novel construction, means being also provided to prevent the porcelain core from cracking when the plug becomes hot, and likewise which prevents leakage when the plug is 25 cold.

A further object of the invention is to provide a device of this character which is easily and simply constructed, inexpensive to manufacture, and one which will be very 30 efficient in operation.

With the above and other objects in view, as will appear as the description proceeds, the invention comprises the various novel features of construction and arrangement of 35 parts which will be more fully described herein and set forth with particularity in the claim appended hereto.

Reference is had to the accompanying drawings forming a part of this application, in which like reference characters indicate the corresponding parts throughout the several views, in which—

Figure 1 is a side elevation of my improved spark plug, partly in section, 45 Fig. 2 is a bottom plan view thereof, and Fig. 3 is an enlarged detailed sectional view of the lower end of the main electrode.

Referring to the drawings in detail, 50 10 designates the porcelain core that is adapted to be positioned in the usual type of casing 11 provided with a wrench engaging surface in the usual manner and having its said lower end externally threaded as shown at 12 so as to permit connection with an engine cylinder. The casing 11 is provided with

internal shoulders 13 thereon that are adapted to receive the lower edge of an enlarged portion 14 formed on the porcelain core 10 that is positioned within the casing, and positioned between the enlarged portion and 60 the shoulders 13 are asbestos or like gaskets 15. The upper gasket is positioned against the upper edge of the enlarged portion and is adapted to be held in true position by the usual type of clamping sleeve 16 that is arranged between the casing and the core as is common to spark plugs of this character, said sleeve being inserted into position to form the upper shoulder in the casing, as 65 specified. These gaskets will prevent the 70 core from breaking, when the plug is hot, as well as to prevent leakage when the plug is cold.

The porcelain plug 10 has positioned centrally therethrough a main electrode 17 which projects from the upper end of the plug as a binding 18 thereon for connecting a lead wire therewith in the usual manner. The main electrode is of the usual size, wherein it extends through the porcelain 80 plug, and the lower end of the porcelain plug is tapered as shown at 19 so as to correspond with an enlarged lower portion 20 of the main electrode, which projects from the plug and below the lower edge of the 85 casing 11, as shown. This enlargement produces a shoulder 21 between which and the lower end of the porcelain core or plug, an asbestos insulating ring or gasket 22 is positioned, so as to prevent heat from being 90 conducted to the core, thereby preventing heating of the latter, as well as preventing leakage when the plug is cold. The lower end of the main electrode 17 is enlarged as 95 shown at 20, in order to provide strength, in addition to forming a shoulder for the attachment and interposition of the gasket or insulator, as described. Formed at the lower end of the electrode and the enlargement 20, is an inverted conical head-like portion 22, 100 the same being provided with diametrically opposite notches 23, the walls of which bevel in opposite directions, while the opposed sides of said enlargement are beveled at right angles to the bevels of the walls of 105 the notches 23, as shown at 24, there being a shoulder 25 formed between the enlargement 20 and the inverted conical enlargement 22 for a purpose to be hereinafter more fully set forth.

Depending from the lower edge or end of the casing 11 is a branch electrode 26, which is angular and has one end portion connected to the lower edge by securing blocks 27, 5 while the free end thereof extends inwardly toward the enlarged head of the main electrode and is spaced therefrom to form the spark gap.

It should be noted that the notched portion 10 is contiguous with and of the same size as the enlargement 20 and by providing the enlarged head 22, producing a shoulder as specified, the firing surface will be protected from oil and like collection of foreign matter, the surfaces draining by reason of the construction described.

Also owing to the fact that the enlarged head of the main electrode is provided with the notches and beveled surfaces on its extremity no continuous surface will be presented that would permit carbon deposits forming thereon. The main electrode is so arranged that one of the beveled faces is disposed adjacent the ends of the branch 25 electrode so that a perfect spark is insured. This will present a flat surface adjacent the end of the branch electrode so that there will be no likelihood of the spark plug missing while in operation. The notches serve 30 to break the continuous lower edge of the extremity, and consequently will prevent carbon deposits forming thereon to short circuit the plug. The beveled faces, owing to their inclination, tend to throw the explosive charge downwardly and prevent any undue backing of gases within the chamber formed between the lower end of the core and the casing, this also being assisted by the lower tapered formation of the plug or core, 35 as specified. Likewise, the provision of the gasket or insulating rings obviates the break-

ing of a plug when the latter becomes hot, as well as to prevent leakage when the plug is cold.

From the foregoing description taken in 45 connection with the accompanying drawings, it is thought that a clear and comprehensive understanding of the construction, operation, and advantages of my invention may be had, and while I have shown and 50 described the device as embodying a specific structure, I desire that it be understood that such changes may be made in said structure as do not depart from the spirit and scope of the invention as claimed. 55

Having thus fully described my invention, what I claim as new and desire to secure by Letters Patent, is:

A spark plug comprising a casing, an insulated core terminating short of the lower 60 edge thereof, a central electrode extending through said core and projecting from the bottom of the same below the edge of the casing, the projecting portion of said electrode being enlarged to provide a shoulder 65 adjacent to said core, an insulator between said enlargement of the central electrode and the core, said core being tapered adjacent thereto, and the lower end of the enlargement of the main electrode having an 70 inverted cone-shaped enlargement provided with opposed beveled surfaces and a groove therein with opposingly beveled notches conforming to the enlargement and disposed at right angles to the beveled faces first mentioned, and a branch electrode projecting from the lower edge of the casing to a point adjacent the extremity of the main electrode. 75

In testimony whereof, I affix my signature hereto.

LEE R. BENN.
